UNITED STATES PATENT OFFICE.

ALEXANDER DOMINICK, OF NEW YORK, N. Y.

DESIGN FOR A SPOON-HANDLE.

SPECIFICATION forming part of Design No. 15,048, dated June 10, 1884.

Application filed April 25, 1884. Term of patent 7 years.

To all whom it may concern:

Be it known that I, ALEXANDER DOMINICK, of the city, county, and State of New York, have invented and produced a new and original Design for Spoon-Handles, of which the following is a full, clear, and exact description.

Reference is to be had to the accompanying drawing, forming part of this specification, and which is a side elevation of my newly designed spoon-handle.

The leading feature of my design consists in annular corrugations gradually decreasing in size from the outer end of the handle inward.

15. C represents a spoon-handle, which is round and gradually decreases in size from the outer end inward. Upon the handle C are formed

annular corrugations D, which gradually decrease in size from the outer end of the said handle inward to correspond with the taper 20 of the handle C. The corrugations D extend from the outer end of the handle C for about two-thirds the length of the said handle, as shown in the drawing.

I claim—

The design for a spoon-handle herein shown and described, the same consisting of annular corrugations D, gradually decreasing in size from the outer end of the tapered handle inward.

ALEXANDER DOMINICK.
